SANITARY ROTARY PUMP

Alexander W. Dietzel, Waukesha, Wis., assignor
to Waukesha Foundry Company, Waukesha,
Wis., a corporation of Wisconsin

Application January 31, 1938, Serial No. 187,732

5 Claims. (Cl. 103—126)

My invention relates to improvements in sanitary rotary pumps, with particular reference to pumps for handling milk and other liquiform foods subject to requirements for a thorough 5 cleansing of all parts after each operation.

My objects are to facilitate complete separation of parts for separate cleansing after each pumping operation; to reduce the number of parts to a minimum; to eliminate all interior 10 packings; to not only provide for complete separation of lubricated driving mechanism from the pumping mechanism, but to provide exterior packing devices for the pump shafts which may be released for separate removal from the exterior side of the pump casing upon withdrawal 15 of the pump piston and shaft members, and which can be reassembled with precision when said shaft members are restored.

A further object is to provide a rotary pump 20 having smooth surfaced internal contours, all of which are easily accessible for cleansing purposes, and none of which are provided with joints or crevices in which infected material or foreign matter may lodge.

Heretofore numerous attempts have been made 25 to provide rotary pumps for liquiform foods which will satisfy official requirements, directed not only to the possibility of sanitation, but to facility in obtaining complete sanitation and thorough inspection. Many problems—some of them quite obscure—have been encountered, and so far as I am aware no satisfactory pump of rotary type has heretofore been produced, which meets requirements for sanitation.

I believe my rotary pump satisfies the requirements of milk inspectors and sanitary boards dealing with dairy products, particularly those requirements which specify that such parts must be free from joints, crevices, and passages which 40 cannot be readily separated, inspected, and cleansed with such facility that regulations ensuring complete sanitation can be reasonably enforced. My improved pump has met with general approval as satisfying these requirements.

Therefore, it is my general object to completely solve the aforesaid problems and provide a rotary pump which will thoroughly satisfy all requirements for sanitation and thorough speedy inspection.

In the drawings:

Figure 1 is a front elevation of my improved pump, with the cap removed, preparatory to withdrawal of the pistons and associated shaft sections.

Figure 2 is a sectional view drawn to line 2—2 of Figure 1, and showing the cap in place.

Figure 3 is an enlarged detail sectional view of one of the packing boxes and an associated fragment of the pump casing and shaft.

Figure 4 is a view similar to Figure 1, with the pistons and shafts removed, and with a portion shown in section, through one of the ports.

Figure 5 is a view of the cap as seen from the inner side.

Figure 6 is a sectional view drawn generally to line 6—6 of Figure 4.

Figure 7 is a view of the removable parts associated with one of the pump cylinders, showing the same in separated relationship.

Figure 8 is a view similar to Figure 3, showing a slight modification.

Like parts are identified by the same reference characters throughout the several views.

My improved pump casing comprises but two 20 separable parts, which may respectively be aptly termed the supporting back wall member 10 and the front wall or cap 11, the latter being normally secured to the back wall by screws 12, having thumb nuts or operating pieces 13. The screws 25 12 pass through apertures in the cap and enter threaded sockets in the back wall member 10, as clearly shown in Figure 2.

The front face of the back wall member 10 is cavitated to provide a pair of intersecting cylindrical cavities 16 and 17, which receive crescent shaped pistons 18 and 19 of a well-known type, operative upon the displacement principle, to alternately draw liquiform material into the respective lobes through one of the ports 22 (or 23) 30 and expel it through the other, the direction of flow being dependent upon the direction of piston rotation. The periphery of each piston is adapted to enter an arcuate socket in the hub of the other piston to sub-divide the lobes into 40 suction and pressure cavities, as is customary in pumps of the described type.

The piston 18 has its hub 25 mounted upon the shaft 26. The piston 19 has its hub 27 mounted upon the shaft 28, and the hubs 25 and 27 are 45 journaled in bearing sockets 29 and 30 formed in the interior face of the cap 11.

Each of the shafts has a portion of larger diameter than the hub receiving portion which extends through an aperture in the back wall 50 member 10, bushings 33 being preferably employed for these apertures. The rear ends of these shaft members are of less diameter than the portions received in the bushings 33 and extend to the exterior through suitable packing boxes. 55

Their exposed ends are connected by coupling sleeves 35 with driving shafts 36 and 37 mounted in a gear chamber 38. In the construction shown, the shaft 36 serves as a driving shaft and transmits motion through the gear wheels 39 and 40 to the shaft 37. The sleeves 35 are preferably keyed to both shafts of the respective pairs and also connected with the driving shafts by cross pins 42, whereby the sleeves are retained in position on the driving shafts while allowing the pump shafts to be withdrawn axially through the pump casing when the cap 11 is removed. The gear casing and pump casing are spaced from each other, but are detachably connected with each other by bolts 45 and 46, the bolts 46 being socketed in spacing sleeves 47, preferably formed integrally with one wall of the gear casing and abutted against corresponding socketed projections 48 on the back wall 10.

20 The back wall 10 is also provided with stud-like projections 50 which are exteriorly threaded to receive the caps 51 and provide packing boxes through which the pump shafts extend. Within each of these packing boxes the associated shaft 25 is provided with a loose collar 55 having an annular flange 56, between which and the associated shaft a packing collar 57 may be received.

This collar 57 is non-metallic, a non-porous composition of rubber and other materials being 30 preferably employed. So-called grease or acid proof composition materials are commercially available for such purposes.

The collars 57 are compressible, and are held 35 against the collars 55 by compression springs 60, each of which has one end seated against an associated shaft shoulder 61. The other end seats against a ring 62 interposed between the spring and the compressible collar 57.

The external diameters of the coiled compression springs 60 exceed the internal diameters of 40 the bushings 33, and, therefore, when the pump cap 11 is removed, the pistons and associated shaft sections may be withdrawn without disturbing the springs 60 and the packing rings or collars. After so withdrawing the shafts, the caps 45 51 may be unscrewed to allow the packing collars and springs to be withdrawn in the space between the pump and the gear case, whereupon all of the parts may be separated for cleansing 50 purposes, as indicated in Figure 7.

Each of the caps 51 has a ground annular face 65 to receive the thrust of the collar 55, and the threaded portion of the cap may engage a compressible packing gasket 66 between it and an annular surface of the member 10 surrounding the stud-like projection 50. Therefore, any liquid escaping into the packing box from the pump cavity will be prevented from following the shaft or otherwise leaving the packing box.

60 The compressible packing collars 57 expand radially under the pressure of the spring actuated rings 62 and completely fill the spaces between the flanges 56 and the shafts with binding pressures in all directions.

65 Liquid in the packing boxes will be prevented from passing around the collars 55 by reason of the ground joints between these collars and the packing box caps 51. The contacting faces of the collars 55 and the cap screws 51 are narrow in the radial dimension, and the cap screws 70 are not in contact with their associated shafts. Also, liquid will be prevented by the gaskets 66 from following the cap screws.

The packing box caps or cap screws 51 are 75 prevented from rotating with the shaft for the

reason that the friction of these caps along the screw surfaces and upon the packing rings 66 is much greater than the friction of the collars 55 on their ground annular faces 65. But the collars 55, 56 and the associated springs 60 rotate with the shaft inasmuch as their combined pressure and friction upon the shafts and upon each other is materially greater than the friction at the ground joints 65. Therefore, wear will occur only at these ground joints 65.

10 In Figure 8 the cap screw 51a has a slightly conical surface at 70 and a gasket 71 is located between this surface and the conically tapered end of the tubular stud 50a. The tapered end of this stud has a projecting annulus 72 which 15 provides anchorage for the gasket 71. If such gaskets are used, gaskets 66 may be dispensed with.

From the foregoing description it will be observed that the pump casing comprises but two 20 members, and that each piston and shaft assembly is permanently connected as a unit. There are no interior packings, joints or crevices in which unsanitary material may lodge, and all working surfaces are completely exposed to view 25 when the casing cap is removed and the piston and shaft units withdrawn.

Also, these piston and shaft units may be withdrawn without disturbing the exterior packing 30 rings and springs on the outer face of the supporting casing member. When the shafts are withdrawn, the springs which are normally seated against the shaft shoulders become seated against the supporting wall of the casing, whereby the packing rings are left undisturbed pending 35 removal of the packing box caps.

With this construction the packing box caps may be removed from the outer side of the supporting wall of the casing, separately cleansed, and restored to their normal positions after 40 cleansing the interior surfaces of the packing boxes and before re-inserting the shafts through the supporting wall from the front side. When the shafts are thus re-inserted there will be an additional compression of the springs when the 45 casing cap is being screwed into place, because the shaft shoulders will then push the springs out of contact with said supporting wall so that they may freely rotate with their associated shafts.

50 I claim:

1. A sanitary rotary pump having a two piece casing, comprising a supporting member and a manually removable cap member, unitary piston and shaft elements each shaft element having 55 smooth surfaced bearings in the supporting member with its power receiving portion projecting exteriorly and reduced in diameter, the other shaft end being normally covered by the cap member, packing rings on the exterior portions 60 of the shafts, ring retaining packing boxes removably secured to the supporting member and subject to thrust of the packing rings, compression springs seated between portions of the protruding ends of said shafts and the packing rings, 65 said springs being of larger diameter than the shaft apertures in the casing member and adapted to seat against said member when the shaft elements are withdrawn, and gaskets between the packing boxes and the supporting casing member cooperative with the packing rings for normally sealing the packing boxes against the escape of fluid from the pump.

2. A sanitary rotary pump having a two piece 70 casing, comprising a supporting member and a 75

- manually removable cap member, unitary piston and shaft elements having shaft ends extending through the supporting member and the other shaft ends normally covered by the cap member, 5 packing rings on the exterior portions of the shafts, ring retaining packing boxes removably secured to the supporting member and subject to thrust of the packing rings, compression springs seated between portions of the protruding ends of said shafts and the packing rings, said springs, packing rings and shafts being normally subject to thrust pressure derived from the cap member, and said packing boxes and supporting member being formed to retain the packing rings and springs in position under reduced pressure when the shafts are withdrawn, subject to restoration of full thrust pressure exerted by the shafts when restored to their normal positions.
- 20 3. In a sanitary rotary pump, free from internal packings and lubricating ducts, and having pump shafts and pistons forwardly removable from a supporting wall, the combination with such supporting wall of driving mechanism spaced from the rear face of the supporting wall, packing boxes on the rear face of said wall and through which the pump shafts normally extend, sets of packing rings in said boxes normally in frictional pressure contact with an associated shaft, and compression springs normally interposed between the boxes and the bearing portion of the shaft in the back wall, said springs being adapted for engagement with the back wall when the shaft is withdrawn.
- 25 4. In a sanitary rotary pump for liquiform foods, the combination with a two part casing, including a supporting wall and a removable cap wall, of a pump shaft having a bearing portion
- mounted in the supporting wall with one end journalled in the cap wall and its other end portion projecting and provided with an annular shoulder exterior to the casing and a reduced power receiving portion beyond the shoulder, a 5 packing unit mounted on the reduced portion and including relatively movable metal housing members having between them an impervious compressible packing ring adapted to be forced into contact with the shaft by pressure exerted 10 upon one of the housing members, a compression spring interposed between said housing member and the shaft shoulder, and a packing box adjustably connected with the supporting casing member and provided with an annular thrust 15 receiving bearing for the other housing member of the packing unit, said packing unit being rotatable with the shaft, and said casing wall and packing box being adapted to support said unit substantially in its operative position when the 20 shaft is withdrawn.
5. In a sanitary rotary pump combination, a supporting wall, free from joints and apertures other than shaft apertures, a detachable front wall free from joints and apertures, piston and 25 shaft assemblies normally held in place by the front wall, with the shafts extending from the front wall through the supporting wall and reduced in diameter at the other side thereof, and packing members normally mounted upon said 30 reduced end portions of the shafts in resilient forwardly exerted thrust relation thereto and distant from the supporting wall, and normally stationary means for enclosing said packing members in frictional thrust receiving relationship 35 thereto.

ALEXANDER W. DIETZEL.
